[57] **CLAIM**

The ornamental design for a tumbler or similar article, as shown and described.

DESCRIPTION

FIG. 1 is a side elevational view of a tumbler or similar article showing my new design;

FIG. 2 is a top plan view thereof;

FIG. 3 is a cross-sectional view thereof taken along line 3—3 of FIG. 2, looking in the direction of the arrows;

FIG. 4 is a bottom plan view thereof; and

FIG. 5 is a side elevational view of a second embodiment of the tumbler or similar article.

FIG. 1.

FIG. 3.

FIG. 2.

FIG. 4.

FIG. 5.
